UNITED STATES PATENT OFFICE.

WILLIAM H. SANGSTER AND JUSTIN C. WARE, OF TITUSVILLE, PA.

IMPROVEMENT IN VALVES FOR STEAM-ENGINES.

Specification forming part of Letters Patent No. 57,386, dated August 21, 1866.

To all whom it may concern:

Be it known that we, WM. H. SANGSTER and JUSTIN C. WARE, of Titusville, in the State of Pennsylvania, have invented certain new and useful Improvements in Steam-Engines; and we do hereby declare that the following is a full, clear, and exact description of the same, reference being had to the accompanying drawings, and to the letters of reference marked thereon.

In the annexed drawings, A represents the boiler of the engine, which is secured upon a furnace to be constructed in any of the known and usual ways. The form of the boiler will be seen in Figure 2, being made concave on the under side, so that a larger surface will be exposed to the action of the fire. One or more flues may be made in this boiler, as may be desired.

B represents the steam-cylinder, which is secured upon the top of the boiler. C represents a metallic frame, which is secured upon the boiler, and which passes back from the steam-cylinder to the rear of the boiler. This frame-work answers the purpose of supporting the shaft upon which the balance-wheel is secured, and also for forming slides for the outer end of the piston-rod.

The steam-chest E is secured upon top of the cylinder B. a represents the pitman which connects the piston-rod with the shaft of the balance-wheel.

The peculiar internal construction of the steam-chest is shown in Fig. 3, where it will be seen that G represents a steam-tube, formed, as shown, with three openings in it—two, as seen at o' o', for the admission of steam from the cylinder, and one, at n, for allowing the steam to escape into the escape-pipe. The pipe G is placed loosely in the steam-chest, with its

openings o o arranged to correspond with and fit over the openings i i in the steam-cylinder.

Upon the pipe G are two small projections, x x, which pass through the openings i i into the steam-chest. These projections are operated upon by means of the piston-head F. At each stroke of the piston the head F strikes against these projections x x, and, moving the pipe G longitudinally, allows the steam which comes in through the pipe k into the chest E to pass alternately into the cylinder through the openings i i. When the piston-head approaches and strikes one of the projections x, it moves the slide-pipe G, so that steam is allowed to enter the cylinder close to the piston-head and force it back to the other end of the cylinder, where the head again moves the slide G, and steam rushes in against the opposite side of the head, as before. Thus, by the operation of the piston-head, these cut-offs are worked. The steam escapes through the openings w and s. J represents the pipe which conveys steam from the boiler to the steam-chest.

Having thus fully described our invention, what we claim as new, and desire to secure by Letters Patent, is—

The steam-chest, the steam-cylinder, and the sliding pipe G, constructed and arranged to operate in the manner and for the purpose herein specified.

In witness that we claim the foregoing we have hereunto set our hands in the presence of two witnesses.

W. H. SANGSTER.
JUSTIN C. WARE.
